Primary Examiner — Garth Rademaker*Assistant Examiner* — Christopher J Matthews(74) *Attorney, Agent, or Firm* — Weide & Miller, Ltd.(57) **CLAIM**

The ornamental design for a cove lighting fixture, as shown and described.

DESCRIPTION

FIG. 1 is a front view of a cove lighting fixture showing the new design;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is a perspective view thereof.

The broken lines indicate unclaimed portions of the article and form no part of the claimed design.
